DESIGN FOR A TEXTILE FABRIC OR SIMILAR ARTICLE

Arnold Zavell, New York, N. Y.

Application April 2, 1940, Serial No. 91,413

Term of patent 3½ years

To all whom it may concern:

Be it known that I, Arnold Zavell, a citizen of the United States, residing in the city of New York, county of New York, and State of New York, have invented a new, original and ornamental Design for a Textile Fabric or Similar Article, of which the following is a specification, reference being had to the accompanying drawing, forming a part thereof.

The figure of the drawing is a plan view of a textile fabric showing my new design.

The arbitrary figures shown in the drawing are raised above the surface, giving the design, as a whole, an embossed appearance.

A complete design unit is included within the dot-an-dash lines and which unit extends through the width of the fabric and is repeated in regular succession along the length thereof.

I claim:

The ornamental design for a textile fabric or similar article, as shown and described.

ARNOLD ZAVELL.
